UNITED STATES PATENT OFFICE

2,139,071

FURNITURE

Frank A. Eichel, New York, N. Y.

Application September 29, 1936, Serial No. 103,095

1 Claim. (Cl. 155—61)

This invention relates to furniture, and pertains more particularly to a seat capable of shifting movement with respect to the floor on which it is supported.

5 It is an object of the invention to provide a simple and inexpensive mechanism permitting reciprocating motion of the seat. It is a further object of the invention to provide a mechanism in which all of the moving parts are beneath the 10 seat, and may be readily enclosed and concealed from view.

Other objects and advantages of the invention will appear hereinafter.

A preferred embodiment of the invention selected for purposes of illustration is shown in 15 the accompanying drawings, in which,

Figure 1 is a top plan view, the upholstering being removed to better disclose the operating parts.

20 Figure 2 is a front elevation, partly broken away.

Figure 3 is an end elevation.

Figure 4 is a section on the line 4—4 of Figure 1, and

25 Figure 5 is an enlarged detail view, in perspective, of one of the pivots.

Referring to the drawings, the apparatus comprises a base frame 1, rectangular in shape, formed of any suitable structural shapes such as 30 the angle irons illustrated. The said base frame may rest directly on the floor as shown, or may be supported on suitable legs or casters.

35 Mounted on the said base frame are a pair of transverse frames 2 comprising upper horizontal members 3, preferably of angle iron, and lower horizontal members 4, preferably of flat iron, connected to the base frame, said upper and lower members being connected by converging members 5, also preferably of angle iron.

40 Extending between the upper and lower members of each transverse frame are a pair of bolts 6 forming vertical axes or pivots for purposes hereinafter described.

The seat frame 7 is rectangular in shape and 45 is preferably formed of angle iron as illustrated in Figures 1 and 4. Any suitable form of upholstery may be applied to the seat frame, and if desired, a back frame 8 of any suitable construction may be secured to the seat frame. At each

corner of the seat frame is preferably secured a depending bracket member 9.

The operating connection between the base frame and the seat frame permitting the desired reciprocating motion is preferably made as follows. Connected to the lower end of each of the depending members 9 is a link 10 which extends upwardly for connection to a transverse bar 11 supported on and pivotally connected to the ends of swinging arms 12. The said swinging 10 arms, in turn, are pivotally connected to transverse frames 2 by means of bolts 6.

It will be apparent that the pairs of swinging arms at each end of the frame will move in unison, being connected by bar 11, but in order 15 to cause the swinging arms at both ends of the frame to move in unison and in the same direction through the same arc the said arms are interconnected. This is preferably accomplished by providing arms 13, formed integrally with 20 swinging arms 12 or rigidly secured thereto, and connecting said arms by means of pivoted link 14. In this manner, as illustrated in Figure 1, the pairs of swinging arms move in the same direction through the same arc, and the movement of the seat frame is reciprocatory in a 25 plane parallel to the floor.

In case it is desired that the seat frame should normally be restored to a central position when the seat is not in use, the spring 15 may be connected to the arms 13 as illustrated in Figure 1. The said spring will be stretched by any movement of the seat and tends to restore the seat to 30 central position.

It will be understood that the invention may be 35 variously modified and embodied within the scope of the subjoined claim.

I claim as my invention:

A seat comprising a base frame, a swinging arm pivoted on a vertical axis on one end of said frame, a swinging arm pivoted on a vertical axis on the other end of said frame, each of said arms having an extension projecting in the opposite direction, a link pivotally connected to said extensions causing said arms to swing in unison, 45 a seat frame supported by said swinging arms, and a spring connected from one of said extensions to the other.

FRANK A. EICHEL.
